UNITED STATES PATENT OFFICE

104,644

DESIGN FOR A CREAM WHIPPER APPLIANCE

Edwin A. Thompson and Tofick L. Hallak,
Kansas City, Mo.

Application March 3, 1937, Serial No. 67,963

Term of patent 7 years

To all whom it may concern:

Be it known that we, Edwin A. Thompson and Tofick L. Hallak, citizens of the United States of America, residing at Kansas City, Jackson County, Missouri, have invented a new, original, and ornamental Design for a Cream Whipper Appliance, of which the following is a specification, reference being had to the accompanying drawing, forming a part thereof.

In the drawing:

Figure 1 is a side elevation of a cream whipper

appliance, showing our new design, the opposite side of the appliance duplicating the side illustrated.

Figure 2 is a top plan view of a cream whipper appliance, showing our new design.

We claim:

The ornamental design for a cream whipper appliance as shown and described.

EDWIN A. THOMPSON.
TOFICK L. HALLAK.
